UNITED STATES PATENT OFFICE

LOUIS E. WARD, OF MIDLAND, MICHIGAN, ASSIGNOR TO THE DOW CHEMICAL COMPANY, OF MIDLAND, MICHIGAN, A CORPORATION OF MICHIGAN

CURTAIN FOR ELECTROLYTIC CELLS

Application filed July 29, 1929. Serial No. 381,795.

This invention relates in general to a curtain-like means for separating anodic from cathodic products of electrolysis. It relates specifically to a sectional type of curtain 5 adapted for use in separating metallic magnesium and chlorine gas produced by the electrolysis of a fused saline bath containing magnesium chloride.

Owing to the high temperature to which 10 such a curtain is exposed, the corrosive action of chlorine and other anodic products and further to the fluxing or erosive action of the fluid hot metal upon ceramic ware in general, and still further to the necessity that the curtain 15 have electrical non-conductive property, the choice of material for such a curtain is somewhat narrow and the details of construction require careful design. Refractory material such as fire-clay or brick shapes is customarily employed and because such material suffers erosion, corrosion, or breakage it is 20 essential that the details of design shall permit the easy substitution of new parts to replace those no longer serviceable. It may be stated, in general, that such pieces of large 25 size are relatively more expensive than those of small size, are more difficult to pack, ship, unpack, and store without breakage and are more readily broken when handled in a re- 30 placement operation. Small pieces, on the contrary, are more cheaply made, more easily packed and transported, easily stored in small space, and can be handled with a minimum of breakage and loss.

I have invented a curtain composed of a plurality of suitably shaped plates of simple design and small size and have invented further means to construct same and means to support said plates in the cell permitting the 40 easy removal and replacement of any single piece even without suspending operation of the cell during such repairs.

To the accomplishment of the foregoing and related ends, the invention, then, consists 45 of the means hereinafter fully described and particularly pointed out in the claims, the annexed drawings and the following description setting forth in detail certain means for carrying out the invention, such disclosed 50 means illustrating, however, but several of

various ways in which the principle of the invention may be used.

In said annexed drawings:—

Fig. 1 is a vertical transverse section of an electrolytic cell employing my invention and 55 adapted to the electrolysis of a fused saline bath for the separation of a metal which will float thereon. Fig. 2 is a vertical longitudinal section through said cell and Fig. 3 is a plan thereof with the cover plates removed 60 to show my improved curtain and other details. Fig. 4 is a side elevation and Fig. 5 65 an edge view of a member of the curtain shown in Figs. 1, 2, and 3. The Figs. 6 and 7 are edge views of modified forms of such 70 curtain member.

Referring to Figs. 1, 2, and 3, showing a type of cell to which my improved curtain is 75 adapted, 1 is a cathode pot set in a furnace adapted to supply initial or control heat for the bath. A single anode or a plurality 80 2 depend in the bath from above and are preferably set in a straight line between opposing cathode surfaces of the pot. The anodes are further preferably supported by adjustable 85 hangers permitting motion in a vertical direction, removal of anodes from the bath, reinsertion therein and for adjusting the depth of dipping in the bath.

In the type of cell illustrated, the pot is 80 provided with an inverted trough 3, adapted to trap liberated metal rising through the bath from the principal cathode surface 4 of the pot. Such metal is shown at 5 in the cross hatched areas. The bath level will be 85 approximately as shown in Figs. 1 and 2. Provision may be advisedly made to lead the light metal so entrapped to a collecting well or gathering zone permitting easy access for removing the so collected metal. Such a collecting well is shown at 15 and the metal collected therein at 17. A second well 6, shown 90 beside well 15 in the plan view Fig. 3, is separated from the latter by the partition 7 and affords access to the cell for the insertion 95 of a dipper or like utensil by means of which sediment or so called sludge may be dredged from the bath while the cell is in operation. The metal collecting in the well 15 may likewise be dipped or otherwise removed from 100

the cell without interrupting operations. One side 3' of the inverted trough adjacent the collecting well 15 is removed to enable the metal entrapped therein to float out into 5 the collecting well. The removed side is shown in dotted lines as 3' in Fig. 2, which dotted lines may be also taken to represent the unremoved portion thereof adjacent the well 6.

10 The curtain separating the anodic from the cathodic bath areas is preferably composed of an assembly of refractory plate-like members having surface projections or other equivalent contours enabling the support 15 thereof upon the cell superstructure. Such a curtain is illustrated in longitudinal cross section in Fig. 2 in plan in Fig. 3, and in transverse section in Fig. 1.

My curtain, prepared in accordance with 20 the present invention, will be seen to consist of a number of refractory plate-like curtain members 18 having a hook-like projection adapted to engage with a corresponding projection upon the trap 3 upon which or from 25 which said curtain members hang in close juxtaposition to form a rectangular enclosure about the anodes. The construction of the individual curtain members, as shown in assembly thereof in Figs. 1, 2, and 3, is clearly 30 shown in Figs. 4 and 5, which latter figures present a side and edge view, respectively, of said separate or individual curtain member, in which the hook-like projection is shown at 19. A variation in design 18' of such curtain member is shown in Fig. 6 and a still 35 further variation thereof 18" in Fig. 7, the variation in Fig. 6 having respect to the projecting portion 20 and that in Fig. 7 to the absence of such projecting portion. The so 40 projecting portion 20 is intended to add height to the curtain when desirable and affords an opportunity to insert therein openings or other variation in contour adapted to engage a tool for handling the curtain member. Each member of the curtain assembly 45 is supported independently of the others and is separately placeable therein and removable therefrom, a distinctive feature being the manner of support which is accomplished by 50 providing, as stated, a hook-shaped projection, engaging with a complementary projection along the upper edge of the collecting trough 3.

The curtain assembly so formed of a plurality of separate removable plate-like members not only serves as a refractory curtain separating anodic from cathodic portions of the bath, but blankets also the otherwise active surface of the trough 3, restricting ca- 55 thodic action thereon, and the consequent liberation of metal not normally collectible in the trap. The curtain members may be constructed of a variety of materials among which are fire-clay or fire-brick materials, 60 sintered magnesia, ceramic ware, such as por-

celain and the like, resistant to the bath at the temperature employed.

Various modifications in the form of the curtain members may be employed without departing from the spirit of my invention 70 and such variations will be evident to one skilled in the art.

When in the course of operation of an electrolytic cell employing a curtain of the type herein disclosed, should one or more members of the assembly become eroded, broken, or otherwise unfit for further service it may be readily replaced with a new member without interrupting the operation of the cell. To do this I provide in a convenient 75 location such new member heated to the approximate temperature of the bath. I then remove one or more of the cover plates 8, which inclose the anodic gas space 10 above the bath, giving access to the member to be removed. Sufficient suction will be carried upon the gas duct 11, connected through the cover 8 with the gas space 10 to draw off the anodic gas together with air entering the opening made by removing the covers. I 80 then insert a suitable tool, engage and remove the disabled curtain member, and then with a similar tool pick up and lower into place the new curtain member, after adjusting which, I then replace the covers. During the 85 operation just described the cell may be continued in operation without loss of output.

My invention is applicable to advantageous use in both large and small scale operation. It is particularly applicable in large 90 scale operations employing a plurality of anodes in a large cell. A sectional curtain for such a cell may be readily constructed of small pieces or plates of the character described to form a rectangular, oval, circular, or other enclosure or partition for leading the anodic gas to the outlet, for covering exposed portions of the pot upon which it is desired to restrict cathodic action, and for separating the floating metal from the anodic 95 products. Such a curtain may be constructed far more cheaply and safely than a large sized single piece curtain and renewals will be confined to the replacement of small pieces for any one breakage whereas when large 100 single piece curtains are used, breakage at a single point will require the substitution of a new piece of large size and cost. Not only are small refractory pieces more cheaply 105 made than large ones but they suffer less breakage in drying, burning, packing, shipping, and storage. They require less boxing and packing materials for shipment, less storage room and less labor in handling, are 110 in many respects highly advantageous relative to large sized pieces. I have found the disadvantage incident to the discontinuous character of the curtain, due to the more or less imperfect joint obtainable in actual practice between the adjoining plate edges, to 115 120 125

present no serious difficulties in operation. It is customary to employ a suction upon the anodic gas chamber of the cell which effectually prevents issue of the chlorine through the joints in the curtain, and such joints are sufficiently close in practice to substantially prevent metal from passing into the anodic compartment from without. In the form of cell construction illustrated in Fig. 1, the bulk of the metal liberated is trapped as indicated, and but a small portion is liberated upon the surfaces of the metal adjacent to the curtain to become later liable to passage in part through the curtain joints into the anodic gas chamber before removal as metal product.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In apparatus of the character described, the combination of a cathode pot, an inverted trough-like trap along the upper limit of the principal cathode surface thereof, a projecting rim along the upper side of said trap, and a curtain assembly including a plate-like non-conducting hook-shaped member engaging with said rim as support therefor.

2. In apparatus of the character described, the combination of a cathode pot, an inverted trough-like trap along the upper limit of the principal cathode surface thereof, a projecting rim along the upper side of said trap and a curtain assembly composed of a plurality of hook-shaped plate-like non-conducting members engaging with said rim as support therefor.

3. In apparatus for electrolyzing a fused salt bath, a plate-like curtain member of refractory material having a hook-like projection adapted to engage with a support so as to be suspended vertically therefrom, and capable of being assembled edge to edge with other like members to form a continuous sectional partition wall or curtain.

4. In apparatus for electrolyzing a fused salt bath, a sectional partition of refractory material to separate anode and cathode products comprising a plurality of generally plate-shaped members each having a hook-like projection engaging a support so as to be suspended vertically therefrom edge to edge with companion members to form a laterally bounded enclosure.

5. In apparatus for electrolyzing a fused salt bath, the combination of a vessel to contain such bath and forming the cathode, anodes depending in said bath and a sectional partition of refractory material to separate anode and cathode products comprising a

plurality of generally plate-shaped members each having a hook-like projection engaging a support therefor so as to be suspended vertically edge to edge with companion members to form an enclosure circumscribing said anodes and dipping below the surface of said bath.

6. In apparatus for electrolyzing a fused salt bath, the combination of a vessel to contain such bath and forming the cathode, an inverted trough-like flange around the inner wall of said vessel adapted to entrap metal rising from the cathode surface and floating on said bath, an upwardly projecting rim along the inner edge of said flange, anodes depending in said bath and a sectional partition of refractory material to separate anode and cathode products comprising a plurality of generally plate-shaped members each having a hook-like projection engaging said rim so as to be suspended vertically therefrom edge to edge with companion members to form an enclosure circumscribing said anodes and dipping below the surface of said bath.

Signed by me this 25 day of July, 1929. 90
LOUIS E. WARD.
